PRODUCTION AND USE OF A UREA SUSPENSION IN OIL

Leslie S. Thornes, Sunbury-on-Thames, England, assignor to The British Petroleum Company Limited, a corporation of Great Britain

Application May 16, 1951, Serial No. 226,557

Claims priority, application Great Britain May 17, 1950

7 Claims. (Cl. 260—96.5)

This invention relates to an improved process for the 15 production of urea in finely divided form and to the refining of petroleum by means of urea in finely divided form.

It is well-known that urea forms crystalline solid adducts with straight chain and slightly branched chain hydrocarbons but does not form solid compounds with naphthenes, highly branched compounds or aromatics. By the use of urea a method has been developed for refining petroleum fractions by resolution of the fractions into chemical types by forming the above solid compounds, separating the 20 non-solid residue and subsequently decomposing the solid compounds.

It is also known that the urea adducts may be decomposed by the action of heat alone with separation of a hydrocarbon phase and a liquid urea phase.

The use of the recovered urea for the production of further amounts of urea-adducts is complicated by the difficulty of returning the urea in a form suitable for the formation of the adducts at a satisfactory reaction rate.

It is an object of the present invention to provide a process for the production of a urea-containing agent for use in the formation of urea adducts. It is a further object to produce urea in the form of a urea-in-oil suspension. It is a still further object to provide an improved process for the production of urea adducts using urea-in-oil suspensions. It is a still further object to provide a process for the refining of petroleum using urea-in-oil suspensions.

According to the present invention a urea-containing agent is produced for use in the formation of urea adducts, by a process which comprises contacting urea with a hydrocarbon oil at elevated temperature, preferably 132—140° C., forming an emulsion of the liquid urea in the oil and shock cooling the emulsion to form a urea suspension in oil by a rapid addition of a hydrocarbon oil at a temperature below that of the emulsion and in an amount sufficient to solidify the urea.

Preferably the hydrocarbon oil is an oil which is to be treated with urea to form urea adducts. The preferred hydrocarbon oils are fractions of petroleum. Preferably urea, in the liquid phase, is contacted with oil at a temperature above 132° C. and preferably in the range 132° C.—140° C.

By operating in the above manner, the urea is converted to small crystals suspended in the oil phase which are readily convertible to urea adducts on subjecting the suspension to adduct forming conditions. Urea recycle when operating in the manner described may closely approach 100%.

Under preferred operation the urea crystals in suspension constitute 50—100% by weight of the hydrocarbon oil employed.

According to a further embodiment of the present invention hydrocarbon oils having a low content of normal paraffins and slightly branched paraffins are produced by a process which comprises treating a petroleum material

2

selected from the group comprising crude petroleum, stabilised petroleum and distillation fractions of petroleum with a urea-in-oil suspension under conditions such that a solid urea adduct is formed, separating a liquid urea adduction raffinate phase comprising naphthenes, highly branched chain hydrocarbons and aromatics from the said product, decomposing the adduct by heat in the absence of water, separating the urea so formed from the urea adduction extract comprising straight chain and slightly branched chain hydrocarbons, contacting the urea with a hydrocarbon oil at elevated temperature, forming an emulsion of liquid urea in the oil and shock cooling the emulsion to form a urea suspension in oil by a rapid addition of a hydrocarbon oil at a temperature below that of the emulsion and in an amount sufficient to solidify the urea, and recycling the urea-in-oil suspension for further reaction with further amounts of the petroleum material.

Preferably the reaction of urea is carried out in the presence of an alkanol of low molecular weight, suitably having less than four carbon atoms/molecule. The preferred alkanol is methanol, other suitable alkanols being ethanol and propanol.

According to a further embodiment of the present invention, hydrocarbon oils are produced by treating a liquid petroleum fraction with a urea-in-oil suspension, an alkanol of low molecular weight and a hydrocarbon diluent, under conditions such that a product comprising a solid urea adduct is formed, separating a liquid phase comprising a hydrocarbon oil from the said product, decomposing the adduct by heat in the absence of water, separating urea and converting it to a urea-in-oil suspension as hereinbefore described, returning the urea-in-oil suspension to the treating stage and recovering said liquid phase, with or without removal of the hydrocarbon diluent contained therein.

Preferably the hydrocarbon diluent is a petroleum fraction, substantially free of compounds forming urea adducts under the conditions of the process, and boiling below the boiling range of the petroleum fraction undergoing treatment. Using a hydrocarbon diluent of this type, the urea adduct, on decomposition by heat, forms a hydrocarbon-methanol phase which may be subjected to fractional distillation whereby a mixture of methanol and hydrocarbon diluent is removed overhead and a normal paraffin containing fraction of the initial feedstock is recovered as bottoms. The overhead fraction of this fractional distillation is then recycled to the urea adduct forming stage.

According to one manner of operation of the process, for the production of fuel suitable for use in gas turbine engines, the hydrocarbon diluent selected is a suitable component for the finished fuel. The liquid phase obtained on separation of the urea adduct from the urea-inactive components is a mixture of branched chain hydrocarbons, naphthenes, aromatics and the hydrocarbon diluent and is suitable for use as a fuel without separation of the diluent.

According to this aspect of the invention, crude petroleum or stabilised crude petroleum or the distillation fraction derived from petroleum is fractionally distilled for the separation of a fraction which is substantially free of compounds forming urea adducts under the reaction conditions of the process of this invention and a higher boiling fraction containing normal paraffins. The higher boiling fraction is then treated with a urea-in-oil suspension as hereinbefore described and the lower boiling fraction is employed as hydrocarbon diluent and wash liquor.

The preferred feedstock to the urea adduction stage is a petroleum fraction boiling in the range 200° C.—350° C. Under the preferred conditions wherein the diluent and

urea adduction feedstock are derived from a common source, the feedstock to a preliminary distillation stage for the separation of diluent and urea adduction feedstock may be a petroleum fraction boiling in the range 100° C.-350° C. Conveniently the diluent and urea adduction feedstocks may be obtained as straight run side streams in the distillation of crude petroleum.

Urea adduction is carried out at a temperature in the range 20° C.-40° C. and, quite conveniently, in the range 20° C.-25° C.

The proportions of reactants in the urea adduction stage depend on the n-paraffin content of the feedstock and the degree of removal of n-paraffins which is desired. It has been shown that approximately one mole of urea is required for each CH₂-group in the n-paraffin. Thus for complete removal of n-paraffins (taken as C₁₃H₂₈) from a gas oil of 200° to 350° C. boiling range containing 15 per cent by weight of n-paraffin, approximately 0.5 lb. of urea per lb. of gas oil feedstock will be required. The proportion of recycle oil in the adduction stage will depend on the proportion of reactants and the consistency of the resulting adduct stream. Using 0.5 lb. of urea per lb. of gas oil, a recycle oil ratio of 1.76 gallons of recycle oil per gallon of gas oil is, in general, satisfactory.

The present invention is illustrated but in no way limited with reference to the figure accompanying the specification which is a flow diagram of a process for the production of a gas turbine fuel wherein urea is recycled to the adduct forming reactor in the manner hereinbefore described.

The reactor 1 fitted with a stirrer 2 receives "make-up" quantities of urea by line 3 and a mixture of feedstock, urea, hydrocarbon diluent, methanol feed oil and recycled oil by line 4. The slurry formed in the reactor passes by line 5 to a rotary filter 6 which is sprayed with further quantities of hydrocarbon diluent from line 7. "Wet" adduct cake is removed by line 8 to decomposer 9. The product from decomposer 9 passes to separator 10 in which a hydrocarbon-methanol phase is removed by line 11, through heater 12 to fractionator 13 in which a normal paraffin containing fraction is removed as bottoms through line 14 and cooler 15. A mixture of methanol and hydrocarbon diluent is removed overhead from fractionator 13 by line 16, through cooler 17 and line 18 and is recycled to the reactor 1 by line 4. A mixture of urea-inactive components of the feedstock together with hydrocarbon diluent is removed from filter 6 by line 19 and constitutes the finished fuel. Liquid urea is removed from the separator 10 by line 20 and is passed to an emulsifier 21 fed with hot feed oil by line 22 from heater 28. The emulsified urea/oil mixture is removed by line 23 and is shock-cooled by admixture with fresh oil feed from line 24 and recycled finished fuel from line 25. The mixture passes through cooler 26 and line 27 for recycle to the reactor 1. "Make-up" methanol passes by line 29 to line 4.

A suitable feed oil to the process is a straight run gas oil boiling in the range 200 to 350° C. A suitable hydrocarbon diluent is a kerosine fraction boiling in the range 100 to 200° C.

In place of urea there may be employed substituted urea, for example, alkyl substituted ureas.

I claim:

1. A process for the production of a urea-containing agent for use in the formation of urea adducts, which comprises contacting urea with hydrocarbon oil at elevated temperature, forming an emulsion of liquid urea in the oil and shock cooling the emulsion to form a urea suspen-

sion in oil by a rapid addition of a hydrocarbon oil at a temperature below that of the emulsion and in an amount sufficient to solidify the urea.

2. A process for the production of a urea-containing agent for use in the formation of urea adducts, which comprises contacting urea with a distillation fraction of petroleum at elevated temperature, forming an emulsion of liquid urea in the oil and shock cooling the emulsion to form a urea suspension in oil by a rapid addition of a hydrocarbon oil at a temperature below that of the emulsion and in an amount sufficient to solidify the urea.

3. A process for the production of a urea-containing agent for use in the formation of urea adducts, which comprises contacting urea with a hydrocarbon oil at elevated temperature, forming an emulsion of liquid urea in the oil and shock cooling the emulsion to form a urea suspension in oil by a rapid addition of a distillation fraction of petroleum at a temperature below that of the emulsion and in an amount sufficient to solidify the urea.

4. A process for the production of a urea-containing agent for use in the formation of urea adducts, which comprises contacting urea with a distillation fraction of petroleum at elevated temperature, forming an emulsion of liquid urea in the oil and shock cooling the emulsion to form a urea suspension in oil by a rapid addition of a further quantity of the said distillation fraction at a temperature below that of the emulsion and in an amount sufficient to solidify the urea.

5. A process as specified in claim 4 in which the distillation fraction is employed in an amount such that the urea suspension in oil contains 50-100% by weight of urea, based on the amount of hydrocarbon oil contained therein.

6. A process as specified in claim 5 in which the hydrocarbon oil with which the urea is contacted is at a temperature in the range 132-140° C. and in which the urea is contacted while in the liquid phase with the said oil.

7. A process for the production of hydrocarbon oils which comprises treating a petroleum material selected from the group comprising crude petroleum, stabilised crude petroleum and distillation fractions of petroleum with a urea-in-oil suspension under conditions such that a solid urea adduct is formed, separating a liquid urea adduction raffinate phase comprising highly branched chain hydrocarbons, naphthenes and aromatics from the said product, decomposing the adduct by heat in the absence of water, separating the urea so formed from the urea adduction extract comprising straight chain and slightly branched chain hydrocarbons, contacting the urea with a hydrocarbon oil at elevated temperature, forming an emulsion of liquid urea in the oil and shock cooling the emulsion to form a urea suspension in oil by a rapid addition of a hydrocarbon oil at a temperature below that of the emulsion and in an amount sufficient to solidify the urea and recycling the urea-in-oil suspension for further reaction with further amounts of the petroleum material.
